UNITED STATES PATENT OFFICE.

JOHN K. NORTHRUP, OF SANTA BARBARA, CALIFORNIA.

ELECTRIC HEATER.

Application filed January 9, 1922. Serial No. 528,049.

To all whom it may concern:

Be it known that I, JOHN K. NORTHRUP, a citizen of the United States of America, and a resident of the city of Santa Barbara, county of Santa Barbara, and State of California, have invented a new and useful Electric Heater, of which the following is a specification.

My invention relates to electric heaters 10 and particularly to that type known as immersion heaters.

One of the objects of the invention is to provide an electric heater which may be used with a hot water bottle to heat the contents 15 of the bottle to a predetermined temperature and then maintain that temperature substantially constant. Another object of the invention is to provide an electric heater of the character recited which is of simple construction and capable of being manufactured 20 at low costs.

My invention possesses other objects and features of advantage, some of which, with the foregoing, will be set forth in the following description of my invention. It is to be understood that I do not limit myself to the showing made by the said description, as I may adopt variant forms of the invention within the scope of the claims.

Referring to the drawings: Fig. 1 is a sectional view on an enlarged scale taken longitudinally thru the heater. Fig. 2 is an elevation of the upper portion of my heater. Fig. 3 is a sectional view, the plane of section being indicated by the line 3—3 of Fig. 1. Fig. 4 is a sectional view thru the upper portion of my device, the plane of section being indicated by the line 4—4 of Fig. 2.

In general terms the device of my invention comprises a suitably protected and insulated heating element of a shape adapting it to be inserted into the filling aperture of a hot water bottle. Means comprising a stopper for the bottle are provided in which the tube is mounted and heat responsive means are also provided for regulating the amount of energizing current supplied to the heating element in accordance with the temperature of the fluid in which the heating element is immersed to the end that the fluid in the bottle may be maintained at substantially a constant temperature.

More particularly my device comprises a tube 2 terminating at its lower end in a bulb 3 closed by the cap 4 which is preferably

permanently soldered or otherwise suitably secured to the bulb. The bulb which is connected to the tube by the neck 5 encloses a chamber 6 which contains a quantity of volatile fluid, such as ether, introduced into the 60 chamber thru a filling aperture normally closed by the screw 7.

At the opposite end, the tube terminates in a hollow head formed of bakelite or comparable non-conducting material comprising 65 the similar front and rear parts 8 and 9 respectively, which are preferably clamped together and about the end of the tube by means of screws 11 located at suitable points in the head part. When the head is assembled upon the tube, a thin coating of cement is preferably applied to the engaged surfaces so as to make the joint tight and to prevent the complete separation of the parts in the event that one-half of the head is removed 70 to give access to the interior thereof. The upper end of the tube is formed with a projecting portion 12 which surrounds the upper end of the pressure transfer tube 13, which extends longitudinally of the main 75 tube and opens into the chamber 6. The upper portion of the main tube is of greater diameter than the lower portion, and the tube 13 passes thru the larger portion but is exposed about its surface in that portion 80 which extends beside the smaller portion of the tube 2. Preferably the tube 2 together with the integrally formed bulb 3 is die cast and the pressure transfer tube 13 is preferably enclosed within the mold in proper 85 position when the casting is made.

The main tube 2 is formed with a flange 14 between which and the adjacent end of the head is rotatably mounted the stopper 16 which is provided with threads 17 adapted to engage the threads in the filling aperture of the hot water bottle 18 suggested in part by the dotted line of Fig. 1. The stopper 16 is also provided with an interrupted flange 21 which preferably surrounds the 100 lower portion of the head and provides a grip with which the stopper may be turned to its seat. Below the flange 14 is a rubber washer 22 which completes the stopper and prevents leakage of the contents of the bottle 105 when it is pressed to its seat in the lower portion of the filling aperture of the hot water bottle. The washer 22 is normally secured in place by the metallic washer 23 which is notched to pass the studs 24 formed 110

on the tube and which are provided for the purpose of retaining the protective casing 26 which surrounds the main tube 2 as indicated in Fig. 1. The casing is preferably 5 apertured to give free access of the fluid in which the device is immersed to the surface of the main tube 2 and the exposed portion of the tube 13. The casing is preferably formed from a flat sheet of material and 10 slightly smaller than the diameter of the part with which it is engaged. The upper portion of the sheet is formed with L-formed notches 27 as shown best in the lower part of Fig. 4, and when pressed into place on 15 the main tube the studs 24 prevent axial movement and the resilient pressure with which the casing grips the main tube 2 tends to prevent rotation of the casing. Thus the casing is normally held in secure position on 20 the main tube but is readily removable if desired.

Arranged within the long chamber enclosed by the main tube is a porcelain core 31 upon the lower portion of which, coils 32 of a suitable resistance wire are bound, the ends of the wire being brought up as shown in Fig. 1, thru the core and terminating in the binding posts 33 and 34 on the inside of the rear half of the head. The 30 coils are insulated from the inner face of the main tube wall by any suitable means, such as by a layer of mica or heat treated sodium silicate. The contact stud 36, molded into the material of the rear portion of the head, 35 is connected by conductor 37 also embedded in the material of the head with the binding post 34, and the contact stud 38, is similarly connected by the conductor 39 with a plate 41 molded into the surface of the head part. 40 The plate 41 is provided with a stud 42 upon which is pivotally mounted the switch arm 43 which may be formed as shown in Fig. 1, and which is provided with an arcuate section 44 provided with gear teeth in mesh 45 with a pinion 46 journaled in the plate 41. The switch arm 43 at its outer end is provided with a contact point 47 which is opposed to the contact point 48 on the switch arm 49 which is pivotally mounted on a stud 51 having the same axis as the stud 42 and extending 50 from the plate 52 fixed on the inside surface of the head and in electrical contact with the binding post 33. A fiber washer 53 is interposed between the two studs to separate the two switch arms, which, it will be understood from the above, control the flow of energy to the heating coil. The switch arm 49 is extended past the pivot stud 51, in the arm 54, which is pivotally connected 55 by means of the turn-buckle 56 with the end of the Bourdon tube 57 which circles about the inside of the head and is fixed on the projecting main tube portion 12 and in communication with the pressure transfer tube 13. The Bourdon tube is insulated from

the lever arm by the block 58 formed of fiber or other non-conducting material and comprising a part of the turn-buckle 56.

Means are provided for adjusting from the outside of the head of the instrument the 70 position of the switch arm 43 so that the temperature at which the contact points 47 and 48 separate, to break the circuit thru the heating coils, may be predetermined and means are also provided for evaluating the 75 adjustment of the arm in terms of the temperature at which the contact is broken. Rotatably journaled in the front part of the head is a shaft 61 slotted on its inner end, as shown, to engage the correspondingly 80 formed end of the shaft 62 on which the pinion 46 is mounted. The outer end of the shaft 61 is provided with a disk 63 of bakelite or fiber and having a pointer 64 thereon, and a spring 66 interposed between the 85 shaft 61 and the inner face of the casing resiliently presses the disk 63 to the head and provides a frictional resistance to its rotation. Arranged radially about the disk 63 are indicia 67 expressing degrees 90 of heat in accordance with the Fahrenheit scale and also an "off" position in which the contacts of the switch arms are out of engagement.

From the above it will be clear that movement of the disk 63 will turn the pinion 46 to vary the position of the switch arm 43, which is then held in position with sufficient rigidness because of the frictional engagement of all the parts. With the device inserted in a hot water bottle and the disk 63 turned to, say, 140 degrees and with a proper connection made to a suitable source of current supply, the current flows thru the heating coils, the hot tube transmitting the heat to the liquid in which it is immersed. With the warming up of the liquid in the bottle the fluid in chamber 6 is volatilized, creating a pressure which is transmitted thru the tube 13 to the Bourdon tube 57 causing 100 it to flex outwardly. The proportion of parts is such that at the predetermined temperature of 140 degrees the flexure of the tube 57 is sufficient to break contact between the switch arms, thus interrupting the current supply and permitting the contents of the bottle to cool somewhat. As soon as the cooling process has carried the temperature below 140 degrees, inward flexure of the Bourdon tube effects the closing of the 110 contact between the switch arms thus renewing the current supply. It is found that a very close regulation of the temperature of the hot water bottle may thus be obtained. Since the chamber 6 is at the extreme end of the tube from which it is separated by a neck of reduced cross section, and is therefore removed from the immediate vicinity of the heating coils as well as surrounded by the liquid in the bottle, it follows that the 115 120 125 130

temperature of the liquid in the bottle is controlling rather than the temperature of the heating coil. If, however, the coils should be energized accidentally, sufficient 5 heat will be conducted thru the neck to vaporize the fluid in the bulb and thus effect the breaking of the circuit before damage occurs. It is also to be noted that because of the exposed portion of the pressure trans- 10 fer tube, undue heating of that tube with consequent undesirable changes in the pressure in the Bourdon tube are avoided.

While I have shown the stopper 16 rotatable on the tube so that the tube as a whole 15 need not be rotated to seat it in the aperture of the hot water bottle, it is obvious that the stopper portion of my device may be rigidly formed with the tube and the entire device rotated to seat in the filling aperture.

20 I claim:

1. An electric heater comprising a tube terminating in a hollow head at one end and a bulb at the other end, an electric heating element arranged in said tube, a 25 quantity of fluid in said bulb, a switch for controlling the flow of current to said heating element, fluid pressure controlled means in said head for operating said switch, and a tube for connecting said bulb to said pressure controlled means and lying outside of 30 said first named tube.

2. An electric heater comprising a tube terminating at one end in a bulb, an electric heating element arranged in said tube, a 35 quantity of fluid in said bulb, a switch for controlling the flow of current to said heating element, fluid pressure controlled means for operating said switch, and an exposed tube for connecting said bulb to 40 said pressure controlled means.

3. An electric heater comprising a tube terminating at one end in a bulb, an electric heating element arranged in said tube, a quantity of fluid in said bulb, a pair of pivoted switch arms, fluid pressure controlled means connected into said bulb for controlling the movement of one of said arms, means for manually adjusting the other arm, and means for energizing said 45 said heating element.

4. An electric heater comprising a tube terminating at one end in a bulb, an electric heating element arranged in said tube, a quantity of fluid in said bulb, a pair of pivoted switch arms, fluid pressure controlled means connected into said bulb for controlling the movement of one of said arms, means for manually adjusting the other arm, means for energizing said heating 50 element, and means for removably mounting said tube in the filling aperture of a container.

5. An electric heater comprising a tube terminating at one end in a bulb, an electric heating element arranged in said tube, a quantity of fluid in said bulb, a pair of normally engaged switch arms, fluid pressure controlled means connected with said bulb for controlling the movement of one of said arms, means for manually adjusting the other arm, indicia for evaluating the adjustment in terms of the temperature at which the pressure controlled means will move its associated arm to open the switch, and means for energizing the heating 65 element.

In testimony whereof, I have hereunto set my hand.

JOHN K. NORTHRUP.
